(57) **CLAIM**

(**) Term: **15 Years**

The ornamental design for a nylon rotatable handle for tool bag, as shown and described.

(21) Appl. No.: **29/677,079**

DESCRIPTION

(22) Filed: **Jan. 17, 2019**

FIG. 1 is a perspective view of a nylon rotatable handle for tool bag showing my new design;

(51) LOC (13) Cl. 03-01

FIG. 2 is a front elevation view thereof, where the back view is a mirror image of FIG. 2;

(52) U.S. Cl.

FIG. 3 is a left side elevation view thereof;

USPC D3/318

FIG. 4 is a right side elevation view thereof;

(58) **Field of Classification Search**

FIG. 5 is the cross-sectional view taken in the direction of lines 2-2 of FIG. 2;

USPC D3/318

FIG. 6 is a top plan view thereof; and,

CPC A45F 5/10; A45F 5/14; B65D 33/06

FIG. 7 is the bottom cross-sectional view taken in the direction of lines 8-8 of FIG. 2.

See application file for complete search history.

The broken lines are included for purposes of illustrating environment and form no part of the claimed design.
